Hazardous Miller
Attorney:

UNITED STATES PATENT OFFICE.

MADS M. LARSEN, OF COLTON, CALIFORNIA.

CURTAIN ATTACHMENT.

Application filed August 24, 1923. Serial No. 659,139.

To all whom it may concern:

Be it known that I, MADS M. LARSEN, a citizen of the United States, residing at Colton, in the county of San Bernardino and State of California, have invented new and useful Improvements in Curtain Attachments, of which the following is a specification.

My invention relates to curtain hangers, and a purpose of my invention is the provision of a curtain hanger of simple and inexpensive construction which is readily attachable to conventional shade brackets so as to be supported in proper position and to thereby effectively operate to suspend curtains in proper position with respect to a window.

It is also a purpose of my invention to provide a curtain hanger of the above described character which is detachably associated with the shade brackets, and which is extensible to permit of its being applied to the shade brackets irrespective of the distance between the brackets.

Although I have herein shown and will describe only one form of curtain hanger embodying my invention, it is to be understood that various changes and modifications may be made herein without departing from the spirit of the invention and the spirit and scope of the appended claims.

In the accompanying drawings,

Fig. 1 is a view showing in perspective a portion of a window casing with conventional shade brackets in applied position thereto, and having applied to the latter one form a curtain hanger embodying my invention.

Fig. 2 is a top plan view of Fig. 1 with portions thereof broken away to reveal parts not otherwise disclosed.

Fig. 3 is a vertical sectional view taken on the line 3—3 of Fig. 2.

Fig. 4 is an enlarged detailed perspective view of one of the terminal portions of the hangers shown in the preceding views.

Referring specifically to the drawings in which similar reference characters refer to similar parts, my invention, in its present embodiment, comprises a pair of rods 15 and 16 both of which are of tubular form with the rod 16 of an internal diameter exceeding that of the rod 15 so that the confronting ends of the two may be telescopically associated with each other for the purpose of shortening and lengthening the rods, as will be understood.

The outer ends of the rods 15 and 16 are constructed to removably fit within the adjacent ends of terminal arms 20, including tubular linear portions 20^a, curved portions 20^b and clips 20^c.

As illustrated to advantage in Fig. 4, the linear portion 20^a of each terminal arm is provided with fluted edges 22 spaced apart to provide a slot which accommodates a securing lip 23 formed on the adjacent end of the corresponding rod 15 or 16. It will be noted that the fluted portions operate to grip the securing lip and to thereby hold the connecting rod in any longitudinally adjusted position within the terminal arm.

The arrangement of the curved portion 20^b of each terminal arm is such as to dispose the clip 20^c in right angular position with respect to the linear portion 20^a. As shown in Fig. 4, the clip is formed integral with the terminal arm and includes a resilient finger 24 having an operating flange 25. The arrangement of the finger 24 is such as to firmly hold the clip upon the shade bracket, it being understood that the shoulder formed adjacent the flange operates to maintain the lip against accidental displacement from the shade bracket, as clearly illustrated in Fig. 3. For permanently securing the clip to a window casing, an extension 26 is formed on each clip and through this extension a nail or other suitable fastening member may be extended and embedded within the window casing, as will be understood.

In Fig. 1, I have shown a window casing having secured thereto shade brackets 27, such brackets being of conventional form and employed for sustaining a shade roller in proper position upon a window frame. In the applied position of the curtain hanger, the clips 20^c are arranged to engage the shanks of the brackets 27 in the manner clearly shown in Figs. 2 and 3. Thus it will be clear that the curtain hanger as a unit is rigidly sustained upon the brackets. The curved portions 20^b of the terminal arms provide free access to the bearing openings of the shade brackets and eliminate the possibility of the shade roller shaft from contacting with the curtain hanger. The terminal arms properly position the rods 15 and 16 with respect to the window frame and curtain shade so that a curtain can be suspended in proper position upon a window. The extensibility of the rods 15 and 16, as well as the sliding con-

nection between the connecting rods and terminal arms, provides the desired range of adjustment to permit of the hanger being applied to shade brackets spaced various 5 distances apart.

What I claim is:

1. A curtain hanger comprising connecting rods extensibly connected to each other, terminal arms slidably receiving said connecting rods, each of said arms terminating in a unitary spring clip arranged at right angles to the connecting rods, said clip comprising a longer outer member and a shorter inner member parallel to each 10 other and removably engaging shade brackets of standard construction, said shade brackets being adapted to support a shade roller without interfering with the curtain hanger.
2. A curtain hanger comprising connecting rods extensibly connected to each other, terminal arms slidably receiving said connecting rods and spring clips integral with said arms and at right angles thereto, each 15 clip consisting of a pair of parallel vertical members, and provided with a shade bracket retaining flange at their lower ends, said clips being adapted to removably engage shade brackets of standard construction, 20 said shade brackets being adapted to support a shade roller without interfering with the 25 curtain hanger.

3. A curtain hanger, comprising connecting rods extensibly connected to each other, terminal arms slidably receiving the connecting rods and having fluted portions to releasably secure the rods within the arms, and spring clips integral with the arms and at right angles thereto and adapted to engage standard shade brackets, said shade 35 brackets being adapted to support a shade roller without interfering with the curtain hanger.

4. A curtain hanger, comprising rods extensibly associated with each other, terminal arms having tubular linear portions slidably receiving the rods, lips formed on the rods, fluted portions on the first portions for releasably engaging said lips, and clips carried by the arms and adapted to engage 40 standard shade brackets, said shade brackets being adapted to support a shade roller without interfering with the curtain hanger.

5. A curtain hanger comprising connecting rods extensibly connected to each other, terminal arms slidably receiving said curtain rods and spring clips integral with said arms and adapted to removably engage shade 45 brackets of standard construction, said clips being provided with fastening means for attachment to a primary support.

In testimony whereof I have signed my name to this specification.

MADS M. LARSEN.
